(12) United States Design Patent (10) Patent No.: US D1,055,634 S
(45) Date of Patent: * Dec. 31, 2024

(54) GRILLING BASKET

(71) Applicant: Daqing Xu, Yangjiang (CN)

(72) Inventor: Daqing Xu, Yangjiang (CN)

() Term: 15 Years

(21) Appl. No.: 35/518,479

(22) Filed: Sep. 4, 2023

(80) Hague Agreement Data

Int. Filing Date: Sep. 4, 2023

Int. Reg. No.: DM/231587

Int. Reg. Date: Sep. 4, 2023

Int. Reg. Pub. Date: Sep. 29, 2023

(30) Foreign Application Priority Data

Jun. 5, 2023 (CN) 202330341353.8
